UNITED STATES PATENT OFFICE.

CHESTER C. SMALL, OF MALDEN, ASSIGNOR TO FREEBORN F. RAYMOND, 2D,
OF NEWTON, MASSACHUSETTS.

HEEL-NAILING MACHINE.

SPECIFICATION forming part of Letters Patent No. 413,973, dated October 29, 1889.

Application filed April 19, 1887. Serial No. 235,317. (No model.)

To all whom it may concern:

Be it known that I, CHESTER C. SMALL, of 5
Malden, in the county of Middlesex and State
of Massachusetts, a citizen of the United
States, have invented a new and useful Im-
provement in Heel-Nailing Machines, of which
the following is a full, clear, and exact de-
scription, reference being had to the accom-
panying drawings, forming a part of this
specification, in explaining its nature.

The invention relates to a heel-nailing ma-
chine having a gang or group of implements
which are used first as awls for puncturing or
forming the nail-receiving holes in the heel-
blank, and then as drivers for driving a gang
or group of nails fed to these holes into the
heel and soles of a boot or shoe to which the
heel is attached. To accomplish this result
it is necessary to employ a templet, and also
20 mechanism for moving the gang or group of
implements to two levels—first, to the lower
level necessary in forming the holes in the
heel-blank, and, second, to the higher level,
when they are reciprocated to drive the fast-
ening-nails. This of course is upon the sup-
position that the boot or shoe is presented to
the nailing devices with the sole uppermost.
Of course if it were presented with its sole
lowermost these movements of the imple-
30 ments would be reversed.

The invention further relates to the com-
bination of a gang or group of instruments
adapted to be used first as awls and then as
drivers with devices for compressing the
heel-blank, and with devices for feeding nails
35 to the templet-holes or to a position to be
driven by the implements when they act as
drivers. I would further say that these de-
vices may be automatic in their action—that
40 is, that the compression of the heel-blank,
feed of the nails, and the two reciprocations
of the head carrying the gang or group of im-
plements may be automatic—or the nail-car-
rier may be moved by hand. I have repre-
45 sented the machine as automatic. I would
further say that when a top lift is to be
spanked it will be necessary to provide the
head carrying the gang or group of combined
awls and drivers, preferably, with a period of
50 rest. These movements, however, preferably

are governed by a cam, and therefore can
take place when desired and be of any re-
quired length.

The invention further relates to various de-
tails of organization and construction, all of 55
which will hereinafter be described.

In the drawings, Figure 1 is a view in ver-
tical central section of a machine having the
features of my invention. Fig. 2 is a view
in elevation of the reciprocating head car- 60
rying the gang or group of implements and
one of the cams for operating the same.
Fig. 3 is a view in vertical central section
illustrating a modified form of the invention.
Figs. 4, 5, and 6 illustrate various positions of 65
the puncturing and driving instruments in
relation to the heel. Figs. 7 and 8 represent
in plan, inverted, and in vertical section the
construction of the top-lift-holding devices.
Fig. 9 illustrates in elevation and in plan, in- 70
verted, one of the forms of the combined awl
and driver. Fig. 10 in similar views illustrates
another form of the combined awl and driver.
Fig. 11 shows in like views still another form
thereof. Fig. 12 is a view of the machine as 75
represented in Fig. 2 in rear elevation.

A is the templet, which is represented as
stationary.

B is a last or work-support. It is mounted
upon the jack-spindle b, which is adapted to 80
be moved upward by means of the toggle-head
b', toggle b², and lever b³, one end of which is
connected with the toggle by a link b⁴ and the
other end of which is connected with a cam
b⁵ on the cam-shaft b⁶.

C is a nail-carrier. It is moved upon the
templet by the cam c into and out of oper- 85
ative position, and is adapted to receive nails
supplied to it automatically from a nail-mak-
ing device.

The construction thus far described is well
known in the art and will be readily under-
stood, and my improved construction is as
follows:

D is a head carrying or supporting a plate 95
d, which holds the puncturing and driving
implements d'. These puncturing and driv-
ing instruments have an end d² somewhat re-
duced in size, and which may be conical, as
represented in Fig. 9, or oval-shaped, as repre- 100

sented in Fig. 11, or star-shaped, as represented in Fig. 10, or of any other form or shape to enable the implement to be forced into the stock of the heel; but of course the points 5 cannot be sharp, like those of the ordinary awl. They must be of a size sufficient to enable them to penetrate and at the same time have a head or surface for driving the fastenings.

- 10 The head D is reciprocated by means of the cams D' D², which are connected with the head D by means of the cam-pins d³. The cams are carried by the shaft d⁴, which is rotated by the shaft b⁶, with which it is connected by the bevel-gear d⁵ d⁶. The cams are timed to move the block D downward sufficiently to cause the implements d' to be forced through the holes of the templet into the stock of the heel any desired distance to 15
- 20 form the necessary holes for the reception of the nails. The head is then lifted and held lifted while the nail-carrier is moved into position to convey nails to the templet-holes. It is then again moved downward by its 25 cams, but not to so great a distance as before, the cams being arranged to move the lower ends of the implements either flush with or slightly above the under surface of the templet. The block is then raised, and, if the 30 heel is to be blind-nailed, is held lifted while the cam for moving the last and presenting the top lift operates to lower the last to permit the insertion of the top lift and an imperforate plate beneath the templet-plate, 35 when the last is immediately lifted by the cam and toggle and the top lift spanked on.

In lieu of cams for reciprocating the head carrying the gang or group of combined awls and drivers, I may use the construction shown 40 in Figs. 3 and 12, which comprises a crank E, connected with a lower cross-head e by means of a pitman e', the end of which is connected with the cross-head by the slotted straps e², and the lower cross-head is connected by rods 45 e³ with the upper head carrying a gang or group of implements. To obtain the longer reciprocation necessary for causing the implements to prick the holes in the heel-blank, I insert between the end of the pitman and 50 the upper surface of the lower cross-head a block e⁴. This block may be moved by hand into position, as described in the Henderson patent, No. 316,894, or it may be automatically moved into position by a cam, as represented in Fig. 3. This mechanism varies 55 from that described in the Henderson patent, in that the pitman is adapted to come in contact with the lower cross-head and move it downward when the block is not interposed, 60 so that the upper head is then moved downward sufficiently to cause the implements to then act as drivers in driving the nails, as the awls are reciprocated first. Upon the starting of the machine, when the pitman is in its 65 highest position, the cam e⁵ upon the shaft e⁶ moves the block e⁴ between the end of the pitman and the upper surface of the cross-

head, and upon the first reciprocation the combined awls and drivers are moved downward sufficiently far to form or prick the holes in the heel-blank. When the pitman reaches its highest position, the block is moved from between its under surface and the upper surface of the cross-head by the cam e⁵, and upon the next downward movement of the pitman its lower end comes in contact with the upper surface of the cross-head, and consequently the throw of both cross-heads is reduced in extent a distance equivalent to the height of the withdrawn block. The block is connected with the slide-bar e⁷, so as to have a vertical movement thereon during the downward and upward movements of the lower cross-head. I would not, however, be understood as confining myself to the especial mechanism described for providing the head supporting this gang or group of combined awls and drivers with the variable throw needed for causing the same gang of implements to act successively as awls and drivers, but may use any equivalent mechanism to that herein described for accomplishing this purpose.

When the form of the invention represented in Fig. 3 is employed and it is desired to attach a top lift without lowering the jack-post after the driving of the nails, the slide-block e⁴ is constructed substantially as therein represented—that is, instead of being shaped to provide the gang or group of implements with two ranges of movement it provides it with three—first, to the lower limit necessary for pricking the holes in the heel, or to the position represented in Fig. 4; second, to the position represented in Fig. 5, or that to which it is moved to drive the attaching-nails for blind-nailing, and, third, to the position represented in Fig. 6—that is, to a position not quite so low as that represented in Fig. 5. This result is obtained by providing the block e⁴ with a series of surfaces of different heights and by constructing the cam e⁵ so as to move the block in relation to the pitman, first, to present the highest surface, then the next lower, and then the lowest surface.

In operation the boot or shoe is placed upon the last or work-support, which is moved into position beneath the templet. The machine is then set in operation, and if it is automatic in its operation the last or work-support is moved upward against the templet to compress the heel-blank. This is immediately followed by the downward movement of the head carrying the gang or group of combined awls and drivers, which then act as awls, and are consequently moved sufficiently to cause their ends to enter the heel-blank to any desired extent to prick it or the holes therein. The gang or group of implements having thus acted as awls are withdrawn, the nail-carrier moved forward to deliver nails to the templet, and the gang or group of instruments are moved downward again, but not so great a distance as before. They then act as drivers, and

are moved to the lower surface of the templet if the heel is to be flush-nailed, and if blind-nailed not quite to the lower surface of the templet. If the heel is to be blind-nailed, 5 the templet is then fed by an imperforate plate below the templet-plate, the last or work-support having been moved downward by the toggle sufficiently to permit this to be done, and it is then moved upward to cause 10 the heel to be moved against the top lift and the top lift to be spanked on.

Having thus fully described my invention, I claim and desire to secure by Letters Patent of the United States—

15 1. In a heel-nailing machine, the combination of a templet with a head suspended from and operated by cams to have a variable reciprocation in relation to the templet, and a gang or group of implements to be used as 20 awls or as drivers mounted on the one end

thereof, adapted to be moved alternately or successively to operate in their two capacities, substantially as described.

2. In a heel-nailing machine, the combination, with a templet and a last or work-support, between which and the templet the heel-blank is compressed, of a head suspended from cams, and thereby provided with a variable throw or vertical reciprocation in relation to the templet, and a gang or group of 25 implements to be used as awls and as drivers mounted on the one end thereof, adapted to be moved alternately or successively to operate in their two capacities, substantially as 30 described.
